UNITED STATES PATENT OFFICE.

JAMES BRIGHOUSE, OF ABERDEEN, SCOTLAND.

SHACKLE.

Application filed November 18, 1925, Serial No. 68,926, and in Great Britain November 17, 1924.

The subject of the invention is a shackle of the sister-hook type in which a hollow screw-threaded boss on one hook-member engages in a corresponding socket in the other hook-member to form a pivot, a binding screw holding the hook-members in operative relationship, the arrangement being such that the boss and socket prevent the load on the hook-members from being transmitted to the screw. 5

In the accompanying drawing Fig. 1 is a plan showing the shackle in open position, Fig. 2 a plan showing the shackle in closed position, Fig. 3 a side elevation, Fig. 4 an end elevation and Fig. 5 a section on the line A--A of Fig. 2.

The shackle shown comprises two complementary hook-members 1, 2 each of approximately S-shape having extremities 1^a, 2^a and pivotally connected at about the centre in scissors fashion.

The pivotal connection of the hook-members is constituted by a hollow screw-threaded boss 3 projecting inwardly from the hook-member 2 and engaging a socket 4 in the hook-member 1, and a binding screw

5 for holding the boss 3 and the socket 4 in operative relationship, the arrangement being such that loads imposed on the hook-members are not transmitted to the screw 5.

Spring-pressed latches 6 cooperate with recesses 7 to lock the hook-members in the closed position.

I claim:

A shackle, of the sister-hook type, comprising two complementary hook-members one of which has a hollow screw-threaded boss and is formed with latch-receiving recesses and the other of which has a corresponding socket engaged by the boss to form a pivot, a binding screw entering said boss and serving to hold said hook-members in operative relationship, said screw being thus free of loads imposed on said hook-members, and spring-pressed latches housed in the second named hook-member and engageable with said recesses, to lock the hook-members in closed position.

In testimony whereof I have signed my name to this specification.

JAMES BRIGHOUSE.
